PETER MACALISTER MACKASKIE, OF CENTRAL, NEVADA, ASSIGNOR OF ONE-HALF TO KEY
PITTMAN, OF TONOPAH, NEVADA.

CHARGE-SUPPLYING MEANS FOR INTERNAL-COMBUSTION ENGINES.

No. 890,522.

Specification of Letters Patent.

Patented June 9, 1908.

Original application filed February 14, 1906, Serial No. 300,997. Divided and this application filed June 26, 1907.
Serial No. 380,961.

To all whom it may concern:

Be it known that I, PETER MACALISTER MACKASKIE, a citizen of the United States, and a resident of Central, in the county of 5 Nye and State of Nevada, have invented a new and Improved Charge-Supplying Means for Internal-Combustion Engines, of which the following is a full, clear, and exact description.

10 This invention relates to certain improvements in charge supplying means for internal combustion engines, and more particularly to means for forcing the air and liquid or gaseous fuel either separately or together 15 under a state of compression into the cylinder and at equal pressures; the present application being a division of my application for rotary engine Serial No. 300,997, filed February 14, 1906, Patent No. 868,678, for 20 rotary engine, granted October 22, 1907.

The invention consists in certain features of construction and combination of parts, all of which will be fully set forth hereinafter and particularly pointed out in the claims.

25 Reference is to be had to the accompanying drawings, forming a part of this specification, in which similar characters of reference indicate corresponding parts in both the figures, and in which

30 Figure 1 is a side elevation of a portion of a rotary engine provided with my improved charge supplying means; and Fig. 2 is a vertical section through the fuel and air tank.

In my improved charge supplying means, 35 I provide a suitable tank 10 sub-divided by a horizontally disposed partition 11 to form a compartment 12 for the liquid fuel, and a compartment 13 for air. Extending through the compartment 11 and having its opposite 40 ends in communication with the separate compartments, is a suitable trap pipe 14 serving to permit the equalization of the pressure between the two compartments and also serving to prevent any moisture of condensation in the compartment 13 from passing 45 into the compartment 12; said pipe 14 also preventing the vapors from the liquid fuel from passing into the compartment 13.

The tank is provided with a suitable draw-off faucet 15 adjacent the bottom thereof, whereby the fuel chamber may be drained, and may also be provided with a faucet 16 communicating with the air compartment 13 just above the compartment 12, whereby any 55 moisture of condensation may be drawn off.

The device is provided with a suitable filling pipe 17 having its inner end terminating in the compartment 12, and having a suitable valve 18, whereby the pipe may be normally kept closed. The air compartment may be 60 provided with a suitable gage 19, whereby the pressure may be readily determined, and may also be provided with any suitable form of safety valve 20 to prevent the generation of too high a pressure within the compartment. 65

The tank above described is connected by separate conduits leading from the air chamber and the liquid chamber to the inlet valve of the engine, and in connection with these conduits is an air pump operated by the engine to maintain the air and liquid under pressure and deliver them at the same pressure to the engine. A liquid pump is also provided for use in pumping the liquid, if desired. 70

To more clearly set forth the operation of my improved means, I have illustrated a portion of a rotary engine 21, supported upon suitable braces 22 and having a rotary shaft 23 extending outwardly through one 80 side of the casing. Mounted upon this shaft is a gear wheel 24 intermeshing with a pinion 25, through the instrumentality of which the two pumps may be operated. As shown, the shaft 23 is the main shaft of the engine, 85 and the pinion 25 is either the same size as the gear wheel 24, or the size of one is a multiple of the size of the other, the relative sizes of the two depending upon the number of inlet valves and the rapidity with 90 which it is desired to operate the pumps. Pivotally mounted upon the shaft 23 is an arm 26 having link connections 27 and 28 to the piston rods 29 and 30 of the two pumps 31 and 32. The piston rod or the connecting link of one of the pumps is operatively connected by a link 33 to a disk 34 carried by the pinion 25. The rotation of the pinion imparts a reciprocating motion to the piston rod 29 of one pump and through the link 27, 95 the arm 26, and the link 28, also imparts a reciprocating motion to the piston of the other pump. The relative sizes of the two pumps 31 and 32 may be determined upon according to the relative proportions of 100 liquid and air which it is desired to deliver to the engine. As shown, the piston rod 29 has a shorter stroke than the piston rod 30, and the pump 31 is accordingly shown as being shorter. 105

Communicating with the pumps and also with the tank 10, there are provided a fuel delivery pipe 35 and an air delivery pipe 36 in communication with the inlet valves of the engine, as clearly set forth in my prior application above referred to. As shown, the fuel pipe 35 is connected to the lower portion of the fuel tank by a branch conduit 37, having two check valves 38 and 39 located therein. Intermediate the check valves, a branch conduit 40 leads from the conduit 37 to the fuel pump 31 and is provided with a hand valve 46. The air delivery conduit 36 leading to the inlet valve is connected to the upper portion of the tank 10 by a branch conduit 41 having check valves 42 and 43 and hand-controlled valves 44 and 45 located therein. For permitting the direct delivery of air from the storage tank to the conduit 36, I provide a conduit 47 having a hand-controlled valve 48 and a check valve 49 therein. Any suitable means may be employed for creating air pressure within the compressed air chamber 13, as, for instance, an operating pump 50 connected thereto by a suitable conduit 51. In the operation of my improved charge-supplying means, a suitable pressure is created in the air chamber and the fuel chamber communicating therewith by means of the hand-controlled pump 50. After the engine is started this pump is no longer needed, and the air pump 32 on the engine serves to take air from the atmosphere and deliver it through the conduit 41 and valves 42 and 45 into the air chamber. The valve 44 is normally closed, as is also the valve 46. A portion of the compressed air in the air chamber 13 passes through the pipe 14 into the fuel chamber, and the liquid fuel passes out through the pipe 37 into the conduit 35 on its way to the inlet valve of the engine. The air in the chamber 13 passes out through the conduit 47 into the conduit 36, and the air and liquid are thus delivered to the engine under identically the same pressure. The pump 32 is continuously pumping air from the atmosphere and compressing it into the compression tank, and the compressed air forces itself and the gasoline to the engine while the pet-cock 52 of the pump 31 is open and the valve 46 is closed, whereby this pump does no work. By closing the valve 45 and opening the valve 44, the air pump 50 will then force the air direct to the engine from the atmosphere and the liquid pump 31 will have to be brought into operation to supply the fuel to the engine. The pet-cock 52 on the pump 31 is then closed and the valve 46 is opened, so that the pump 31 draws liquid from the tank through the check valve 38 and the conduit 40, and forces it back through the conduit 40, check valve 39, and

conduit 37 on its way to the engine. The pump 31 is used as a pump only in case of emergency, as, for instance, an air leak in chamber 13, and the pump 50 is used only in starting the device. The tank 10 can be used as a pressure tank to start the engine with compressed air, if desired, but the main or principal object is to have the air and the liquid fuel under compression in the tank 10, so that the compressed air will force itself and the gasoline up to the engine cylinder under equally balanced pressure and in proper proportion.

Having thus described my invention, I claim as new and desire to secure by Letters Patent:

1. In combination with an internal combustion engine, a tank having a transverse partition dividing it into an upper air chamber and a lower chamber for liquid fuel, an air pressure pipe leading from the air chamber to said engine, a liquid fuel supply pipe leading from the liquid chamber to said engine, a trap pipe connecting the air chamber and the fuel chamber and means for delivering compressed air to said tank.

2. In combination with an internal combustion engine, a tank having a transverse partition dividing it into an upper air chamber and a lower chamber for liquid fuel, an air pressure pipe leading from the air chamber to said engine, a liquid fuel supply pipe leading from the liquid chamber to said engine, a trap pipe leading through said partition from said air chamber to said liquid chamber and means for delivering compressed air to said tank.

3. In combination with an internal combustion engine, a storage tank having an air chamber and a liquid fuel chamber in communication with each other, an air pump adapted to deliver air to said air chamber or to said engine, a liquid pump adapted to deliver liquid from said liquid chamber to said engine and conduits establishing communication between said engine and said air chamber, and between said engine and said oil chamber.

4. In combination with an internal combustion engine, a tank, a conduit from said tank to said engine, an air pump for creating air pressure within said tank to force liquid through said conduit to the engine, means for delivering air to said engine, and a liquid pump for withdrawing liquid from said tank and delivering it to said engine.

In testimony whereof I have signed my name to this specification in the presence of two subscribing witnesses.

PETER MACALLISTER MACKASKIE.
